UNITED STATES PATENT OFFICE.

JAMES H. KIDDER, OF LAWRENCE, MASSACHUSETTS.

IMPROVEMENT IN PEN-WIPERS.

Specification forming part of Letters Patent No. 142,480, dated September 2, 1873; application filed April 18, 1873.

To all whom it may concern:

Be it known that I, JAMES H. KIDDER, of Lawrence, in the county of Essex and State of Massachusetts, have invented a certain new and useful Improved Pen-Wiper; and that the following is a full, clear, and exact description of the same, reference being had to the accompanying plate of drawings.

This invention relates to an improved pen-wiper in which are combined two brushes, a water-receptacle, and an ink-well, the construction and arrangement of which are fully hereinafter described.

In the accompanying plate of drawings my improved pen-wiper is illustrated, Figure 1 being a plan view; Fig. 2, a central vertical section in plane of line $x-x$, Fig. 1; and Fig. 3, a vertical section in plane of line $y-y$, Fig. 2.

A in the drawings represents a stand or frame, constructed, in the present instance, of a bottom box, B, surmounted for a portion of its top by a rack, c, of any of the ordinary constructions for the reception of pen-holders, &c., and adapted as an ink-well, C²; D and E, two brush-heads having bunches of bristles, a a. These brush-heads D and E are arranged horizontally within the bottom box B, so that the outer ends of the bristles of each brush-head abut against each other, and for their location in the box B, as aforesaid, the brush-heads are secured to frames b. These frames b have end pieces c, between which the brush-heads are fastened, and plates d for covering nearly the whole of one side of the bristles of each head, which covering-plates at the outer ends of the bristles are bent downward, forming, when the two brush-heads are located as described, a throat, f, leading to the bristles at the abutting ends, and thus insuring the proper

insertion of the pen between the bristles. The brush-head frames are not fastened in the box B, but are held in position by their flanges g overlapping the upper edges of the box B, and the brush-head D is within and under the plane of the pen-rack C, resting also, by its end pieces c, upon the shelf E' of the box B.

Under the construction and arrangement of parts above described obviously the bristles are in the most effective position for use as a wiper for pens, and the brush-heads are free to be removed from and inserted in the box or frame B at pleasure; and the box B, if desired, may be filled with water for moistening the bristles, thus rendering the bristles more adapted for the cleansing of pens; F, a casing at one side of the bottom box B; and G, a brush-head. This brush-head G is attached to a frame, h, and that frame h is located in the casing F in a manner similar to that described for the brush-heads D E, and in the location of the brush-head G the outer end of its bristles are against the end of the box B, and between the two a pen-holder can be placed, and thus held when not in use.

Having thus described my invention, what I claim, and desire to secure by Letters Patent, is—

The water-box B having the supporting-shelf E', in combination with the plates d d having the throat f, and the brush-heads D E, all constructed and arranged as herein shown, for the purpose specified.

The above specification of my invention signed by me this 10th day of April, 1873.

JAMES H. KIDDER.
